(57) **CLAIM**

The ornamental design for a skin massage roller, as shown and described.

DESCRIPTION

FIG. 1 is a perspective view of a skin massage roller showing my new design;

FIG. 2 is another perspective view thereof;

FIG. 3 is a front view thereof, the rear view being a mirror image of FIG. 3;

FIG. 4 is a top view thereof;

FIG. 5 is a bottom view thereof;

FIG. 6 is a right side view thereof;

FIG. 7 is a left side view thereof;

FIG. 8 is an enlarged view of a roller showing a state in which the roller is arranged horizontally;

FIG. 9 is a cross-sectional view taken along line 9-9 in FIG. 8; and,

FIG. 10 is a horizontal sectional view taken along line 10-10 in FIG. 8.
